UNITED STATES PATENT OFFICE

WILLIAM FRIEDMAN, OF NEW YORK, N. Y., ASSIGNOR TO LUPE, INC., OF NEW YORK, N. Y., A CORPORATION OF NEW YORK

TOILET ACCESSORY

Application filed July 26, 1929. Serial No. 381,121.

This invention relates to toilet accessories, and more particularly to such devices as are carried by women and commonly termed "vanity boxes" for holding a make-up material, such as face powder.

The objects of the invention are to provide an improved toilet accessory of this sort which is adapted to be used with "loose powder" as distinguished from a "powder compact"; to enable the powder to be securely retained against inadvertent spilling or loss; to provide for very easy application of some of the powder to a powder puff; to secure immediate closure of the container upon removal of the powder puff; to thus obtain a toilet accessory for loose powder having means for readily dispensing the powder similar to the operation of obtaining powder from the present day compact; to provide a structure wherein the parts may be readily blanked out with easily constructed tools; to thus promote quantity production and economical manufacture; to enable the parts to be readily assembled; to secure simplicity of construction and operation; and to obtain other advantages and results as may be brought out in the following description.

Referring to the accompanying drawings in which like numerals of reference indicate similar parts throughout the several views;

Figure 1 is a plan of an open toilet accessory embodying my invention;

Figure 2 is a sectional view thereof on line 2-2;

Figure 3 is a similar sectional view showing the dispensing retainer being depressed;

Figure 4 is a plan of a modified construction of toilet accessory in open position; and

Figure 5 is a sectional view on line 5-5 of Fig. 4.

In the specific embodiment of the invention illustrated in said drawings, the reference numeral 1 indicates the body or box portion of the toilet accessory, this box or body portion being adapted to receive a make-up material in powder form. Preferably, as shown, I provide an outer cover 2, and, closing the usual opening 3 of the box, but adapted to be enclosed also by said outer cover 2, is an inner cover which I prefer to

call a dispensing retainer 4. Both the cover and the retainer are preferably hinged, as at 5 and 6 respectively, to the body, so they may be opened independently of each other, and have suitable snap fastening means as usual for retaining them releasably closed. The dispensing retainer is intended to be opened only for such purposes as inspection and filling the box 1, the retainer having means for passing the powder therethrough as required.

The dispensing retainer 4, forming an essential part of the present invention, is of such nature that it is normally closed to prevent escape or spilling of the powder from the box 1, but has a construction enabling it to automatically permit escape of a limited amount of powder when properly manipulated as by rubbing or tapping. The openings through which the powder thus escapes, nevertheless, will close as soon as pressure is removed. Of the various ways of accomplishing this action, I have illustrated herein a retainer composed of a resilient sifter plate 7 and juxtaposed thereto is an imperforate or closure plate 8. Preferably the resilient plate 7 is stamped from a single piece of material providing an outer rim 9 forming a closure around the edge of the box opening 3, which in the present showing is circular but not necessarily so. The middle portion of said plate is preferably cut away for a restricted area at least sufficient to receive the shank of a rivet hereinafter referred to. From this central cut-away portion, the plate is stamped or otherwise provided with a plurality of emanating slots 10, herein shown as radial and extending part way to the edge of the plate. It is to be noted that the slots 10 open into the common cut away portion at the middle part of the plate so that the slots and cut away portion are all connected openings. As a result of this construction, the plate provides a plurality of resilient segments 11 which can be flexed by pressure near or at the center of said plate.

While the toilet accessory might be used under some conditions without addition of

other parts, that is, used with the slotted resilient plate alone, it is preferable to associate the closure plate 8 therewith for preventing escape of powder except when the 5 powder is desired. The closure plate furthermore is utilized to act as a feeder for the powder to the resilient or dispensing plate 7. As shown, the closure plate is of a diameter greater than the distance between 10 outer ends of aligned slots 10 in the dispensing plate, and shaped to underlie all of said slots and close the same when the two plates are flatwise together or in juxtaposed position. For securing the plates together, I 15 have shown a washer 12 overlying the inner ends of the segments 11 on the opposite side of the resilient plate from the closure plate. A rivet 13 passes through the washer and the closure plate securing those parts in fixed 20 relationship, the ends of the segments projecting between said closure plate and washer and slidable with respect thereto. As a result of this construction, the washer and closure plate may be depressed thereby depressing the inner ends of said segments the 25 effect of which is to separate the plates from each other at their peripheries. Depression of the imperforate or closure plate causes air in the container to be expelled, 30 and since the plates are separated at such time, the air passes out through slots 10 in the dispensing plate. It is to be noted that this flow of air will carry powder with it from the container, and for this reason I 35 term the imperforate plate 8 a powder lifter. When pressure is removed from the washer, the parts return to normal position by virtue of the resiliency of the material 40 of the upper plate, and the closure plate thereupon seals the slots so that powder will not escape inadvertently. As shown, I prefer to offset the tip ends of the segments, as at 14, at the place where they enter under the washer, so as to provide a substantially even 45 or plane surface for the dispensing retainer for wiping the powder puff across.

Obviously detail changes and modifications may be made in the construction and use of my improved toilet accessory without departing from the spirit or scope of the 50 invention, and I do not wish to be understood as limiting myself to the exact construction shown and described except as set forth in the following claims when construed in the light of the prior art.

For instance, it is not to be understood 55 that I restrict the invention as disclosed to any definite proportion or relation of slots and segments. In Figures 1, 2 and 3, the 60 slots are shown as relatively narrow and the segments of greater width. In the construction shown in Figures 4 and 5, I have shown dispensing plate 15 and closure plate 16 thereunder, the dispensing plate having 65 relatively wide slots 17 and narrow seg-

ments 18. As in the construction above described, I show a washer 19 above said segments connected to the closure plate by rivet 20. In both constructions, it will be observed that the free ends of the segments 70 are directed toward a common center or close to a common point, and will act to centralize the closure plate and washer by engagement of the rivet with the ends of the said segments. 75

Having thus described my invention, I claim:

1. A device of the character described comprising a resilient plate having a plurality of segments in substantial continuation of the surface of the plate so as to be readily wiped, said segments being separated by slots, said slots being connected to each other and arranged so as to permit the segments to be flexed. 80

2. A device of the character described comprising a dispensing retainer having a resilient dispensing plate, said dispensing plate having a plurality of segments separated by slots, said slots being connected to each other and arranged so as to permit the segments to be flexed, and a closure plate adapted to normally close said slots. 85

3. A device of the character described comprising a resilient plate substantially in a plane having a cut away portion with slots emanating therefrom thereby providing a plurality of segments adapted to be independently flexed and providing a surface readily wiped with a powder puff while the segments are in either normal or flexed position. 90

4. A device of the character described comprising a resilient plate having a cut away portion with slots emanating therefrom thereby providing a plurality of segments adapted to be independently flexed, and a closure plate adapted to normally close said slots and cut away portion. 95

5. A device of the character described comprising a resilient plate having a plurality of segments in substantial continuation of the surface of the plate so as to be readily wiped, said segments being separated by radial slots, said slots being connected to each other and arranged so as to permit the segments to flex and providing a surface readily wiped with a powder puff while the segments are in either normal or flexed position. 100

6. A device of the character described comprising a resilient plate having a plurality of segments separated by radial slots, said slots being connected to each other and arranged so as to permit the segments to flex, and a closure plate adapted to normally close said slots. 105

7. A device of the character described comprising a resilient plate having a plurality of segments, a closure plate on one 110

side of said resilient plate, and a washer on the other side of said resilient plate, said closure plate and washer being connected so as to flex a plurality of said segments at one time.

8. A device of the character described comprising a resilient plate having a plurality of segments, a closure plate on one side of said resilient plate, a washer on the other side of said resilient plate, and a rivet or the like connecting said closure plate and washer so as to flex a plurality of said segments at one time.

9. A device of the character described comprising a resilient plate having a plurality of segments having free ends close to a common point, a washer and a closure plate on opposite sides of said resilient plate overlying said free ends of the segments, and a rivet opposite the said free ends of said segments and connecting the closure plate and washer, engagement of the ends of the segments with said rivet retaining said closure plate and washer in relatively centralized position with respect to said plurality of segments.

10. A device of the character described comprising a resilient plate having a plurality of segments having free ends directed toward a middle part of said plate, the marginal inner end portions of said segments being offset, a washer in said offset portions of said segments thereby providing a substantially smooth surface on which to wipe a powder puff, and a closure plate on the other side of said segments from said washer, said washer and closure plate being connected together.
